OTHER PUBLICATIONS

The "Richer House 2-in-1 Wall Mounted Floating Shelves Set of 3" disclosed on Amazon.com with an URL: <https://www.amazon.com/gp/product/B0BGPTSBK1?th=1>, published with a first available date of Sep. 28, 2022 by Richer House was obtained directly from the inventors, Weilong Zhu and Lingzhao Lian. The Amazon store Richer House is owned by the applicant, Shenzhen jifu keji youxian gongsi.

Primary Examiner — Nathan M Johnston(74) *Attorney, Agent, or Firm* — ScienBiziP, P.C.(57) **CLAIM**

The ornamental design for a wall shelf, as shown and described.

DESCRIPTION

FIG. 1 is a front, right and top perspective view of a wall shelf, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the wall shelf that form no part of the claimed design.

1 Claim, 8 Drawing Sheets(56)
